WEATHER STRIP

Filed Nov. 9, 1927

UNITED STATES PATENT OFFICE

HOWARD E. SMITH AND LOUIS F. JULIEN, OF DETROIT, MICHIGAN, ASSIGNEES TO
CHAMBERLIN METAL WEATHER STRIP COMPANY, OF DETROIT, MICHIGAN, A COR-
PORATION OF MICHIGAN.

WEATHER STRIP.

Application filed November 9, 1927. Serial No. 232,022.

This invention relates to weatherstrips and the object of the invention is to provide a weatherstrip particularly adapted for use with swinging steel casement windows to provide a seal between the steel window sash and its frame.

Another object of the invention is to provide a weatherstrip formed of spring metal arranged to bindingly engage the sash frame, the weatherstrip being provided with an integral extending spring metal flange adapted to engage the window frame when the sash is closed to close the space between the sash and frame.

15 A further object of the invention is to provide a metal weatherstrip of spring metal adapted to be clipped onto a steel casement sash, the strip being arranged to allow for variation in width of the sash frame.

20 A further object of the invention is to provide a weatherstrip which will provide a seal even when the sash cannot be pulled up tightly into the frame.

These objects and the several novel features 25 of the invention are hereinafter more fully described and claimed and the preferred form of construction by which these objects are attained is shown in the accompanying drawings in which—

30 Fig. 1 is an elevation of a swinging steel casement window embodying our invention.

Fig. 2 is an enlarged section taken on line 2—2 of Fig. 1 showing the strip as it is moved into contact with the window frame.

35 Fig. 3 is a similar section taken on line 3—3 of Fig. 1 showing the window sash drawn up into the frame.

Fig. 4 is a section through the strip before being mounted on the sash.

40 As shown in Fig. 4 the weatherstrip is formed of sheet bronze which is fairly thin in order to have flexibility and springiness. This bronze strip is rolled to form an arcuate portion 1 crosswise of the strip having an edge 2 which is turned over and is provided with a hemmed edge 3 which is formed of double thickness at this point. The edge 4 of the arcuate portion 1 is formed on a comparatively short radius providing a turned in portion 5 having a bead 6 rolled therein. Extending from the bead 6 is the sealing flange 7 which tends to spring outwardly and at the outer edge the flange 7 is provided with

an outturned portion 8 having a hemmed or double thickness edge 9. The weatherstrip 55 is installed on the window sash as shown in Fig. 2. The portion 4 is engaged over the outer edge 10 of the steel sash and the hemmed edge 2 is engaged over the edge 11 of the sash. The portion 1 is made arcuate in form so that 60 the edge 2 may be stretched tightly to engage it over the edge 11 of the sash thus causing the portion 1 to engage the sash with a tension to hold the strip in place. The steel sash will vary usually about one thirty-second of 65 an inch from standard size and this arcuate portion 1 provides sufficient material to allow the edges to be stretched slightly during installation on the sash and thus the strip accommodates itself to slight variations in sash 70 widths. As will be understood from Fig. 4 the bead 6 normally tends to extend into the arcuate portion 1 and when installed in the sash, as will be understood from Fig. 2, this bead engages against the inner edge of the 75 sash with sufficient tension to hold the strip on the sash. The bead 6 is rounded as shown and the flange 7 which extends from the bead 6 is bent on a slight radius at the point where it connects with the bead 6 in order to prevent 80 breakage. It will thus be seen that movement of the flange 7 is absorbed in the rounded bead 6 which will take up the sealing action 85 of the flange without tending to break and provides a spring support for the flange 7. When the strip is assembled on the sash as shown in Fig. 2 the tension of the parts holds the strip in place on the sash and if desired the edge 2 of the strip may be pushed into the putty which holds the glass 12 in place 90 though this is not necessary to hold the strip in place. As the window is swung to the closed position the double thickness edge 8 of the flange 7 engages the window frame 13 as shown. As the sash is drawn tightly into 95 the frame this flange 7 is turned to the position shown in Fig. 3 so that it engages the window frame with considerable tension thus preventing passage of wind, snow or rain between the window sash and frame. When 100 the window is again opened the flange 7 again springs out to the position shown in Fig. 2 and thus the flange 7 will seal the space between the sash and frame even when the sash is not fitted tightly into the frame. One of 105 the particular features of this strip is that it

may be secured to the sash without drilling holes or changing the sash in any manner and the strip may be readily removed or replaced at any time without inconvenience.

5 The strip may be installed without removing the sash from the frame and when once installed will remain in operative position as long as it is in use.

An essential feature of the invention relates in the provision of a clamping portion to engage over the edge of the window frame to which is attached a weather closing portion. In the form of the invention shown in the accompanying drawing the strip is 15 bent upon itself to form a recess substantially U shaped in cross section to receive the sash edge, the portion of the strip on the outer face of the sash being transversely bowed and of a width greater than the width 20 of the portion engaging the inner face of the sash and normally extending thereover with the terminal edge occupying a plane somewhat beyond the plane occupied by that portion of the strip adapted to engage the 25 inner face of the sash. The sash edge is also formed to provide the projection or seat and in placing the strip on the sash the outer portion must of necessity be sprung outwardly to open the recess to permit assembly of the 30 strip on the sash. The terminal edge of the outer portion is then sprung over the shoulder or ledge to engagement with the seat and thus the strip is retained in place under tension with the inner portion thereof tightly 35 engaging the inner face of the sash. The use of retaining screws or other means of mechanically fastening the strip in place is thus obviated.

The weather closing portion extends outwardly from the inner end of the inner edge of the inner sash engaging portion 5 and in closing the sash the terminal edge 8 of this weather closing portion first engages the frame and, as the sash is continued in its 45 closing movement, this edge is caused to move downwardly on the face of the frame and thus the action of this resilient weather closing portion also tends to maintain the strip in place on the sash.

50 From the foregoing description it becomes evident that the device is very simple and efficient in operation, will not easily get out of order, may be very easily installed and provides a device which accomplishes the objects described.

Having thus fully described our invention, its utility and mode of operation, what we claim and desire to secure by Letters Patent of the United States is—

60 1. A weatherstrip comprising a spring metal strip rolled to arcuate form crosswise of the strip and having an inturned edge for engagement with a steel casement sash, the opposite edge of the strip being inturned and terminating in a bead adjacent the center of

the arcuate portion adapted to engage behind the steel casement sash and a flange extending at an angle from the said bead and having an outturned terminal edge adapted to yieldably engage the window frame as the 70 sash is closed.

2. A weatherstrip comprising a spring metal strip rolled to arcuate form in cross section and having an inturned portion terminating in a bead adjacent the center of the 75 arcuate portion, and a flange extending outwardly from the said bead and having an outturned hemmed terminal edge, the opposite edge of the strip being provided with an in-turned hemmed edge.

80 3. A weatherstrip comprising a spring metal strip rolled to arcuate form crosswise of the strip and having an inturned edge for engagement over a steel casement sash, the opposite edge of the strip being inturned to engage behind the steel casement sash and having a return bent flange for yieldably engaging the window frame as the sash is closed.

4. A weatherstrip comprising a spring 90 metal strip rolled to arcuate form crosswise of the strip and having an inturned edge, the opposite edge being provided with an in-turned portion return bent on itself and having a bead rolled into the strip at the return bend, the terminal edge of the return bent portion being outturned as and for the purpose described.

5. A weatherstrip comprising a spring metal strip rolled to arcuate form in cross 100 section and adapted for engagement over a steel casement sash, the said arcuate portion having an inturned portion engaging the inside of the sash and an extending flange for engaging the window frame as the sash is closed.

6. A weatherstrip comprising a spring metal strip having an inturned edge for engagement over a steel casement sash, the opposite edge of the strip being inturned to engage behind the steel casement sash and prevent removal of the strip from the sash and an extending spring flange for engaging the window frame as the sash is closed.

7. A metal weather stripping comprising a 115 clamping portion to engage over the edge of a window frame and a weather closing portion resiliently attached thereto.

8. In a metal weather stripping, a clamping portion for the edge of a metal window 120 frame comprising substantially parallel walls and spring means pressing said walls together, and a weather closing portion resiliently attached to one of said walls.

9. In a metal weather stripping, a clamping portion comprising substantially parallel walls adapted to engage the edge of a metal window frame, said walls formed from a single piece of spring metal and connected by a bend shaped to exert a spring action 130

pressing said walls together, and weather closing means resiliently attached to one of said walls.

10. In a metal weather stripping, a clamping portion comprising substantially parallel walls adapted to engage the edge of a metal window frame, said walls formed from a single piece of spring metal and connected by a bend shaped to exert a spring action 10 pressing said walls together, a strengthening lip formed upon the outer edge of one of said walls and weather closing means resiliently attached to the other of said walls.

11. Metal weather stripping for a window- 15 portion in which the parting of the frame and sash is in a direction substantially parallel with the window comprising a clamping portion adapted to engage the edge of the window sash, and a weather closing means 20 resiliently attached to said clamping means and extending at an angle therefrom, said weather closing means adapted to be located in the channel between the frame and sash and to press against said sash to form a 25 weather closure.

12. Metal weather stripping for a window- portion in which the parting of the frame and sash is in a direction substantially parallel 30 with the window, comprising a clamping portion having two substantially parallel walls formed of the same piece of sheet metal, with a spring bend between said walls adapted to exert spring tension pressing them together, and a weather closure portion also formed 35 from the same piece of metal and extending in angular resilient relationship to one of said walls, said weather closure member having a portion adapted to lie within the channel between the sash and the frame of said 40 casement window and abut a portion of said sash to form a weather closure therewith.

13. Metal weather stripping for a window- portion in which the parting of the frame and sash is in a direction substantially parallel 45 with the window, comprising a clamping portion having two substantially parallel walls formed of the same piece of sheet metal, with a spring bend between said walls adapted to exert spring tension pressing them together, and a weather closure portion also formed 50 from the same piece of metal and extending in angular resilient relationship to one of said walls, said weather closure member having a portion adapted to lie within the channel be- 55 tween the sash and the frame of said casement window and abut a portion of said sash to form a weather closure therewith, and a lip formed upon the outer edge of the other of said walls.

60 14. A metal weather stripping for a window-portion in which the parting of the frame and sash is in a direction transverse to the plane of the window, comprising clamping means adapted to engage the edge of the 65 metal casement frame, and a resilient weather

closure means attached to said clamping means and adapted to extend in substantially parallel relationship thereto when depressed by the edge of the sash when closed.

15. A metal weather stripping for a window-portion in which the parting of the frame and sash is in a direction transverse to the plane of the window, comprising a clamping portion formed of two substantially parallel walls of the same piece of spring metal 75 with a bend of said metal therebetween adapted to exert spring tension on said walls toward each other, a reverse bend of the same metal at the end of one of said walls, and a resilient weather closing member also of the 80 same piece of spring metal resiliently attached to said wall by said reverse bend and adapted to be depressed into substantially parallel relationship with said wall by the sash of said casement window when closed. 85

16. A metal weather stripping for a window-portion in which the parting of the frame and sash is in a direction transverse to the plane of the window, comprising a clamping portion formed of two substantially parallel walls of the same piece of spring metal 90 with a bend of said metal therebetween adapted to exert spring tension on said walls toward each other, a reverse bend of the same metal at the end of one of said walls, and a resilient weather closing member also of the 95 same piece of spring metal resiliently attached to said wall by said reverse bend and adapted to be depressed into substantially parallel relationship with said wall by the sash of said casement window when closed and a bead on the outer edge of said weather closure member, said bead offset from the bend connecting said two walls so as to lie beyond it when the said sash is closed. 100

17. The combination with a casement sash and frame therefor, the sash being formed with an edge portion in part overlying the frame when in closed relation therewith and having a ledge formed at a distance from and 110 parallel with the terminal edge, of a spring metal weather strip bent upon itself to provide a substantially U shaped portion to engage over the terminal edge of the sash, the portion of the strip on the outer face of the sash edge being adapted to engage over the 115 said ledge to retain the strip in place on the sash edge, and a weather closing portion resiliently attached to the portion of the strip 120 engaging the inner face of the sash.

18. The combination with a casement sash and frame therefor, the sash being formed with an edge portion in part overlying the frame when in closed relation therewith and having a ledge formed at a distance from and 125 parallel with the terminal edge, of a spring metal weather strip bent upon itself to provide a portion to engage over the terminal edge of the sash, the portion of the strip on the outer face of the sash being transversely 130

bowed and adapted to be sprung over the said ledge to force the portion of the strip on the inner face of the sash into engagement therewith under tension and to retain the strip in place on the sash edge, and a weather closing portion attached to that portion of the strip engaging the inner face of the sash.

19. The combination with a casement sash and frame therefor, the sash being formed with an edge portion overlying the frame when in closed relation therewith and further having a part arranged to provide a seat, of a spring metal weather strip bent upon itself to provide a recess to receive the sash edge, the portion of the strip on the outer face of the sash being formed at its terminal edge to engage the seat and to hold the portion on the inner face of the sash in place under tension, and a weather closing portion attached to said inner portion of the strip.

20. The combination with a casement sash and frame therefor, the sash being formed with an edge portion overlying the frame when in closed relation therewith and further having a ledge like portion of a form to provide a seat at a distance from the terminal edge, of a spring metal weather strip bent upon itself to provide a recess adapting the same to engage over the sash edge, the portion of the strip on the outer face of the sash being greater in width than the portion engaging the inner face of the sash and terminating in an edge portion normally lying in a plane at a distance beyond the inner portion whereby,

in placing the strip on the sash with said terminal edge engagement with the seat, the said outer portion is of necessity sprung outwardly forcing the inner portion of the strip into tight engagement with the sash under tension, and a weather closing portion connected with the inner edge of said inner portion of the strip.

21. The combination with a window frame and a swinging sash having a ledge like portion providing a seat, of a sash having a ledge like portion providing a seat, of a spring metal weather strip formed with a recess to receive an edge of the sash, the portion of the strip on the outer face of the sash having a terminal edge to engage the said seat and being of such form that in assembling on the sash the strip is held in place under tension, and a weather closing portion extending outwardly from the inner edge of that portion of the strip on the inner face of the sash arranged to frictionally engage the frame as the sash is closed in a manner tending to force the strip onto the sash.

22. A metal weather strip for use in closing the interstice between a window sash and its frame, comprising a portion adapted to be clamped over the edge of the sash, and a portion adapted for yieldable engagement with the frame.

In testimony whereof, we sign this specification.

bowed and adapted to be sprung over the said ledge to force the portion of the strip on the inner face of the sash into engagement therewith under tension and to retain the strip in place on the sash edge, and a weather closing portion attached to that portion of the strip engaging the inner face of the sash.

19. The combination with a casement sash and frame therefor, the sash being formed with an edge portion overlying the frame when in closed relation therewith and further having a part arranged to provide a seat, of a spring metal weather strip bent upon itself to provide a recess to receive the sash edge, the portion of the strip on the outer face of the sash being formed at its terminal edge to engage the seat and to hold the portion on the inner face of the sash in place under tension, and a weather closing portion attached to said inner portion of the strip.

20. The combination with a casement sash and frame therefor, the sash being formed with an edge portion overlying the frame when in closed relation therewith and further having a ledge like portion of a form to provide a seat at a distance from the terminal edge, of a spring metal weather strip bent upon itself to provide a recess adapting the same to engage over the sash edge, the portion of the strip on the outer face of the sash being greater in width than the portion engaging the inner face of the sash and terminating in an edge portion normally lying in a plane at a distance beyond the inner portion whereby,

in placing the strip on the sash with said terminal edge engagement with the seat, the said outer portion is of necessity sprung outwardly forcing the inner portion of the strip into tight engagement with the sash under tension, and a weather closing portion connected with the inner edge of said inner portion of the strip.

21. The combination with a window frame and a swinging sash having a ledge like portion providing a seat, of a sash having a ledge like portion providing a seat, of a spring metal weather strip formed with a recess to receive an edge of the sash, the portion of the strip on the outer face of the sash having a terminal edge to engage the said seat and being of such form that in assembling on the sash the strip is held in place under tension, and a weather closing portion extending outwardly from the inner edge of that portion of the strip on the inner face of the sash arranged to frictionally engage the frame as the sash is closed in a manner tending to force the strip onto the sash.

22. A metal weather strip for use in closing the interstice between a window sash and its frame, comprising a portion adapted to be clamped over the edge of the sash, and a portion adapted for yieldable engagement with the frame.

In testimony whereof, we sign this specification.
